INVENTOR
ALFRED SPANEY

BY
Conrad v. Detenbeck
his ATTORNEY

UNITED STATES PATENT OFFICE.

ALFRED SPANEY, OF PIERMONT, NEW YORK.

FINGER-RING.

1,178,186.

Specification of Letters Patent. Patented Apr. 4, 1916.

Application filed April 3, 1915. Serial No. 18,960.

To all whom it may concern:

Be it known that I, ALFRED SPANEY, a citizen of the United States, residing at Piermont, Rockland county, in the State 5 of New York, have invented certain new and useful Improvements in Finger-Rings, of which the following is a full, clear, and exact specification.

My invention relates to improvements in 10 jewelry, and the same has for its object more particularly to provide a ring comprising a plurality of parts or members of which certain may be worn separately as complete rings or in combination with the 15 remainder of said parts or members; or with certain thereof only to form a complete ring.

Further, said invention has for its object to provide a ring comprising a complete 20 ring member and a plurality of supplemental ring members adapted to be fitted upon or conformed to said main ring member in order to increase the size of the ring.

Further, said invention has for its object 25 to provide a ring comprising a plurality of members, the outer ones of which are adapted to removably receive a complete ring member, and supplemental ring members whereby the design or the color scheme 30 or jewel combination may be varied at will.

Further, said invention has for its object 35 to provide a ring comprising a plurality of members which may be so assembled and secured together as to present the appearance of a single complete ring, and still permit of the removal or changing of some of its intermediate parts, at will.

To the attainment of the aforesaid objects and ends, my invention consists in the 40 novel details of construction, and in the combination, connection and arrangement of parts hereinafter more fully described and then pointed out in the claims.

In the accompanying drawings forming 45 part of this specification, wherein like numerals of reference indicate like parts, Figure 1 is a top view showing one form of finger ring constructed according to and embodying my said invention; Fig. 2 is a 50 similar view showing the main ring member combined with the adjoining supplemental ring member only; Fig. 3 is a similar view showing the main ring member entirely separated from the supplemental ring 55 members; Fig. 4 is a side view of the assembled ring shown in plan at Fig. 1; Fig. 5

is an end view of Fig. 4; Fig. 6 is a detail side view of the main ring member shown in plan at Fig. 3; Fig. 7 is a detail side view showing the lower portions of the 60 several ring members, the means for securing the supplemental ring sections together and for supporting the main ring member therein; the several parts being shown in separated relation, and Fig. 8 is a similar 65 view showing the said parts in properly assembled relation.

In the accompanying drawings the ring is shown composed of three parts or members of which the confined, inner or main 70 ring member 10 is a complete ring, and is preferably tapered from its top to its bottom so as to be slightly wedge-shaped in appearance when viewed from its edges. The opposite sides of said ring, at about its 75 horizontal center, are provided with cut-away portions forming shoulders 11, 11. 12 denotes a first supplemental or confining ring member which is composed of two separated members 12^a, 12^b, arranged at 80 slight angles to each other and united at their opposite sides by transverse connecting members 13, 13, and at their lower central portion by two separated connecting members 13^a, 13^b arranged in separated relation to each other. The sides of said annular members 12^a, 12^b are partly cut-away as far as the lower edges of the transverse connecting members 13, 13.

The upper horizontal edges of the connecting members 13, 13 serve as supports upon which the shoulders 11, 11 of the ring member 10 are adapted to rest when said ring member 10 is inserted in position intermediate the members 12^a, 12^b of the supplemental ring member 12. The lower edge of the ring member 10 is provided with a recess or notch 10^a to receive the separated connecting members 13^a, 13^b at the lower edge 90 or base of the supplemental ring member 12. 100 15 denotes the outer or second supplemental ring member which is also composed of two annular parts 15^a, 15^b united at their opposite sides by transverse connecting members 16, 16 whose upper surfaces serve 105 as a support upon which the lower edges of the horizontal connecting members 13, 13, of the first supplemental ring member 12 are adapted to rest. The supplemental ring member 15 is further provided at its lower edge or base with a single connecting member 16^a which is adapted to fit intermediate 110

the two connecting members 13^a, 13^a when the several ring elements are assembled as shown at Figs. 1 and 4.

When the ring is not upon the finger of the wearer, the several ring members or parts 10, 12, 15, are maintained in proper adjustment relative to each other by the engagement of the connecting members 13, 16, and the shoulder 11 in conjunction with the recess 10^a and the lower connecting members 13^a, 16^a. The several parts are then held to assembled form by a slight frictional engagement of the sides of said members 10, 12, 15 with each other.

15 The ring member 10 together with the supplemental ring members 12 and 15 are so constructed, so far as ornamentation and design are concerned, that when the same are assembled, as shown at Fig. 1, the several 20 parts will form a harmonious symmetrical design. Further, the said members or parts are so constructed and arranged that the ring member 10 may be individually removed from the remaining supplemental 25 ring members 12 and 15, without separating the latter from each other, and another ring member 10 having a different color of jewels substituted in place of the member removed; or only the supplemental ring member 12 may be removed and another substituted in place thereof, or the ring member 10 together with the surrounding supplemental ring member 12 minus the outer supplemental ring member 15 may be 30 used as a complete ring.

It will be noted that by means of my improved ring construction, I am enabled to provide a ring which may be varied or modified, at will, so far as color scheme of 40 the jewels and ornamentation or design of the mountings are concerned, to make the ring harmonize or conform to the garment of the wearer or to permit of any arbitrary change or modification desired by the 45 wearer.

Having thus described my said invention, what I claim and desire to secure by Letters Patent is:—

1. A finger ring of the character described comprising a main ring member, and an independent supplemental ring member conforming to said main ring member and embracing the same, substantially as 50 specified.

55 2. A finger ring of the character described comprising a main ring member, and an independent supplemental ring member conforming to said main ring member and frictionally embracing the same, substantially as specified.

3. A finger ring of the character described comprising a main ring member, an independent supplemental ring member conforming to said main ring member and embracing the same, and means for holding 60

said ring members properly positioned relatively to each other, substantially as specified.

4. A finger ring of the character described comprising a main ring member, and a supplemental ring member composed of two parts secured together in separated relation and frictionally embracing said main ring member, substantially as specified. 70

5. A finger ring of the character described comprising a main ring member, a supplemental ring member composed of two parts secured together in separated relation and receiving said main ring member intermediate the same, and means for holding said 75 main ring member and supplemental ring member properly positioned relative to each other, substantially as specified.

6. A finger ring of the character described comprising a main ring member, a supplemental ring member composed of two sections, means for securing said sections together in separated relation; said supplemental ring member receiving said main ring member, and means on said main ring member engaging with the securing means on said supplemental ring member for holding said main ring member properly positioned within said supplemental ring member, substantially as specified. 80 90

7. A finger ring of the character described comprising a main, complete ring member, a supplemental ring member receiving said main ring member; said supplemental ring member being composed of two sections arranged in separated relation, and means for securing said sections together at their opposite sides and at their bases, substantially as specified. 100

8. A finger ring of the character described comprising a main, complete ring member, and a supplemental ring member receiving said main ring member; said supplemental ring member being composed of two axially aligned sections arranged in separated relation to each other, and means for securing said sections together at their opposite sides and at their bases, substantially as specified. 105 110

9. A finger ring of the character described comprising a main, complete ring member having shoulders at its opposite sides and a recess in its base, a first supplemental ring composed of two sections, connecting members at its opposite sides and at its base, and a second supplemental ring member also formed of two sections, connecting members at their opposite sides and at their bases; the recess in said main ring member, and the connecting members at the bases of said supplemental ring members, engaging with each other to hold said several ring elements duly positioned relative to each other, substantially as specified. 115 120 125

10. A finger ring of the character described comprising a main, complete ring member, 130

holding means arranged upon the periphery thereof, and a supplemental ring member receiving said main ring member; said supplemental ring member being composed of 5 two correspondingly-shaped sections arranged in separated relation and at slight angles to each other, and means for securing said supplemental ring sections together at their opposite sides and at their bases, 10 said securing means serving further to engage with the holding means on said main ring member for maintaining the latter properly positioned within said supplemental ring member, substantially as specified. 15

11. A finger ring of the character described comprising a complete ring member having notches arranged upon the periphery thereof, and a supplemental ring member receiving 20 said main ring member; said supplemental ring member being composed of two correspondingly-shaped sections arranged in separated relation to each other, a plurality of horizontal connecting members for securing 25 said supplemental ring sections together at their opposite sides and at their bases, serving also to engage the recesses on said main ring member whereby to hold said

main ring member properly positioned within said supplemental ring member, substantially as specified. 30

12. A finger ring of the character described comprising a main, complete ring member, holding means arranged upon the periphery thereof, a first supplemental ring member 35 receiving said main ring member; said supplemental ring member being composed of two correspondingly-shaped sections arranged in separated relation to each other, means for securing said supplemental ring 40 sections together, serving also to engage the holding means on said main ring member, and a second supplemental ring member composed of two correspondingly-shaped sections secured together in separated relation and receiving said main ring member and said first supplemental ring member 45 jointly therein, substantially as specified.

Signed at the city of New York, in the county and State of New York, this 31st 50 day of December, one thousand nine hundred and fourteen.

ALFRED SPANEY.
